UNITED STATES PATENT OFFICE.

WARREN McARTHUR, JR., OF CHICAGO, ILLINOIS.

WICK-BURNER.

1,152,742.

Specification of Letters Patent.

Patented Sept. 7, 1915.

Application filed January 17, 1914. Serial No. 812,696.

To all whom it may concern:

Be it known that I, WARREN McARTHUR, Jr., a citizen of the United States, residing at Chicago, in the county of Cook and State 5 of Illinois, have invented a new and useful Improvement in Wick-Burners, of which the following is a specification.

This invention relates more particularly to wick burners for tubular lanterns and is 10 particularly desirable for that class of lanterns in which the burner cone is secured to the globe supporting plate and is moved with the same to and from the wick tube. A lantern of that general character is shown, 15 for instance, in my Patent No. 1,070,152, dated August 12, 1913.

The object of this invention is to simplify the construction of the burner to facilitate 20 the assembling of the parts and to render the burner strong and durable.

In the accompanying drawings: Figure 1 is a perspective view of the complete burner. Fig. 2 is a sectional elevation of the same in the plane of the wick raiser shaft, on an 25 enlarged scale. Fig. 3 is a top plan view of the burner. Fig. 4 is a top plan view of the lower part of the burner with the wick raiser shaft, the wick tube being shown in section. Fig. 5 is a sectional elevation of the 30 upper part of the burner on line 5—5, Fig. 2. Fig. 6 is a sectional elevation of the lower part of the burner, on the same line. Fig. 7 is an elevation of a modified construction of the burner. Fig. 8 is a sectional elevation of the same, on an enlarged 35 scale. Fig. 9 is a sectional elevation of the upper part of the burner on line 9—9, Fig. 8, and Fig. 10 is a similar view of the lower part of the burner on the same line. Fig. 40 11 is a perspective view of the lower part of the burner.

Referring to Figs. 1—6, the burner there represented comprises four main parts, a lower body part A, an upper body part B, 45 a wick tube C which connects the upper and lower parts, and a wick raiser or ratchet shaft D to which the ratchet wheels 15 are secured.

The lower body part A comprises a circular shank 16 which is designed to be seated in the burner socket of the oil pot in the usual way and which has in its flat bottom a slot for the lower end of the wick tube. The lower part A comprises further a horizontal 50 portion 17 which extends outwardly from this shank and is provided with large air

passages 18, and has an upstanding marginal flange 19. The latter is provided on opposite sides with notches 20 for the wick raiser shaft D.

The upper body part B of the burner comprises an upwardly tapering portion 21 having large air passages 22 and terminating in a substantially horizontal top plate 23 which is provided with a slot for the upper 60 end of the wick tube and with fine perforations outside of said slot. This upper part of the burner comprises further a horizontal portion 24 which extends outwardly from the lower end of the portion 21 and is provided with a downwardly extending marginal flange 25 having notches 26 for the wick raiser shaft, which notches coincide with the notches 20 in the flange of the lower part. The horizontal portion 24 is provided with 70 large air passages 27 similar to those formed in the lower horizontal portion 17, so that the air can pass freely in an upward direction through the laterally projecting marginal portion of the burner when the latter is 75 arranged in the air chamber of the lantern.

The vertical flanges 19 and 25 of the two parts of the burner overlap or telescope one into the other and the wick raiser shaft is arranged in the coinciding notches of these 80 flanges. In assembling the parts the shaft with the ratchet wheels secured thereto is laid in the notches of the lower part and the upper part is then applied to the lower part and secured thereto in any suitable 85 manner, for instance, as shown in Fig. 2, by means of the wick tube which is clenched at its upper and lower ends over the upper and lower parts of the burner body, respectively, and secures the two parts together 90 with the wick raiser shaft confined between the meeting or lapping edges of the same, or the outer marginal flange of the burner can be bent or clenched over the inserted part, as also shown in Fig. 2.

This construction of the burner permits the ratchet wheels to be permanently secured to the shaft before the latter is placed in the burner body and avoids the difficulty often experienced with wheels working loose in 105 burners in which the shaft and the wheels are separately applied and the shaft is introduced through openings in the wall of the burner and thrust through the central openings in the ratchet wheels. The marginal flange of one body part of the burner 110 rests against the shoulder formed by the

other part and is held against this shoulder by the wick tube which ties the two parts together, thereby forming a strong and rigid structure in a very simple manner.

5 The flat top surface of the body portion of the burner, which is arranged on a level with the upper end of the wick tube, takes the place of the usual wings, flies or tips located at the upper end of the wick tube.

10 In the modified construction of the burner represented in Figs. 7-11, the marginal flange 30 of the lower part A of the burner is provided with an internal annular bead 31 which forms a shoulder against which 15 the annular flange 32 of the upper part B rests. This flange is so narrow that it stands above the wick raiser shaft and notches 33 for the shaft are therefore formed only in the flange of the lower part.

15 20 I claim as my invention:

1. A wick burner having a body comprising a marginal portion having annular horizontal upper and lower walls provided with air passages, an upwardly extending portion 25 also provided with air passages and with a flat top, a downwardly extending shank, a

wick tube secured with its upper end in said flat top and with its lower end in the bottom of said shank, and a wick raiser shaft journaled in said marginal portion.

2. A wick burner comprising a body composed of a lower and an upper part provided with lapping marginal flanges, the lower body part comprising a shank adapted to be seated in a burner socket, a perforated horizontal portion extending outwardly from said shank and an upstanding marginal flange, the upper body part comprising a horizontal perforated portion, a downwardly extending marginal flange on the same and an upwardly extending central portion having a flat top, and a wick tube arranged with its upper end in the upper end of said top portion and with its lower end in the lower end of said shank.

45 Witness my hand this 9th day of January, 1914.

WARREN McARTHUR, JR.
